UNITED STATES PATENT OFFICE.

WILLIAM A. SALTER, OF CEDAR POINT, KANSAS.

TWO-CYCLE GAS-ENGINE.

No. 876,020.

Specification of Letters Patent.

Patented Jan. 7, 1908.

Application filed April 18, 1907. Serial No. 368,896.

To all whom it may concern:

Be it known that I, WILLIAM A. SALTER, a citizen of the United States, residing at Cedar Point, in the county of Chase and State of Kansas, have invented new and useful Improvements in Two-Cycle Gas-Engines, of which the following is a specification.

The object of this invention is to enable the utilization of an explosive gas mixture, in what is known as an internal combustion or explosion gas engine, with materially greater economy in the amount of gas consumed, and higher relative efficiency in the amount of power produced therefrom, with a greater range of speeds at which the engine will work and produce economical power, by maintaining a higher purity or nearer perfect mixture, of the power gas charge in the combustion chamber on all different speeds of the engine, than has heretofore been attained.

A further object is to provide an engine, which for a given size or weight shall produce the greatest amount of power.

To attain this end, generally speaking, my invention consists of a combustion chamber and a compression chamber having a connecting gas passage or passages of large area, so as to allow of quick transfer of power gas even under light compression, a piston, and an exhaust valve in the combustion chamber mechanically operated and capable of adjustment and control so that it will open and close at different points or periods relative to the revolutions of the crank shaft and the location of the piston in its reciprocating motions.

My invention further consists, in an engine as above described having a variably timed exhaust valve, and having a throttle in the inlet power gas passage, so that the volume of the successive power gas charges entering the compression chamber can be varied at the will of the operator.

My invention further consists, in an engine as above described, having an exhaust valve variably timed, a throttle in the inlet gas passage, and means for operative control and adjustment of the exhaust valve and gas throttle.

As my invention contemplates the application of these improvements to the most highly organized gas engines of the present day, I do not confine myself to the details of construction and organization herein shown, but when specifying a particular construc-

tion or organization intend to include well known equivalents therefor.

The improvement claimed is hereinafter fully set forth.

The characteristic defect of the gas engine of the present day, is the difficulty of maintaining a perfect mixture of gas (consisting of explosive vapor) and air, in the combustion chamber at varying ranges of speeds, and especially is this so in the two cycle engines, or where there is a working stroke to each revolution of the crank shaft.

In gas engines as at present in general use, the piston does not approach closely to the cylinder head, and there is always remaining in the combustion chamber, to dilute the incoming fresh charge of power gas, as many cubic inches of burned exhaust gases as there are cubic inches of space between the cylinder head and the head of the piston at its extreme point of travel toward the cylinder head, this being called the clearance space.

In the two cycle engine as at present in general use and practice, this objection is present to a greater degree than in the four-cycle engine, and this type of engine is also very inflexible, having only one speed at which it will attain highest working power and efficiency, due to the relative ratio of the cylinder capacity and the clearances of the inlet and exhaust ports. The two cycle engine is generally regarded as being good for what is one speed, or what is very close to one speed, and that one near the maximum at which the engine is capable of being driven. When it is undertaken to reduce by throttling or reducing the quantity of fresh gas entering into the combustion chamber, the residue or remaining burned exhaust gases is so large in proportion to the fresh charge, (to the impairment of the explosive charge, and the useless compression of this burned "dead" gas constituting a brake on the working of this type of engine,) that where any great range of varying speeds is desired, the two cycle type of engine has generally been regarded as an undesirable type, or as inferior to the four cycle engine.

My invention is designed to provide a gas engine of the two cycle type in which the objections above stated will be satisfactorily obviated, and its leading feature consists in the employment of a variably timed exhaust valve, adjustably controllable, and transfer ports and gas passages, with variable com-

pression in the compression chamber by varying the volume of working power gas admitted to that chamber.

Taking as a starting point, that point in the revolution of the crank shaft where the piston has reached its highest point of travel, that is, the point nearest the cylinder head, the exhaust valve is timed to open at approximately 125° of the crank shaft's revolution from that point, on the working stroke of the piston. When the engine is working at its greatest power, and receiving a charge of gas nearest equal in volume to its piston displacement, the exhaust valve is then timed to close at a point where the piston has moved backward on its compression stroke, equal to the clearance space in the engine. The fresh charge of gas injected in front of the piston, then crowds the burned exhaust gas forward and the exhaust gas products are totally expelled (if there has been no intermingling of the old and new charge) the exhaust valve closing at the proper moment to catch the full charge of fresh pure gas, which is then compressed and fired or exploded in the working stroke. Or when the inlet gas passage leading into the compression chamber is throttled and a charge of gas smaller than the volume of the piston displacement enters the compression and combustion chamber, the exhaust valve is held open then or suspended from its seat for a longer time during the compression stroke of the piston, and just closes as the fresh gas in front of the piston pushes out (and expels) the exhausted burned gas product in front of it, the valve thus catching and the piston compressing the smaller fresh charge of gas for firing and working stroke, but in this latter case, it is obvious that as the volume of the gas charge is less than where a full charge is admitted, therefore with the smaller charge the compression in the combustion chamber is less than where a full charge is used, resulting in a less powerful explosion, and a slower burning combustion so that the crank shaft revolves at a slower working speed than where the full charge of power gas is used. The same cycle of operations result in all the graduated adjustments of which the engine is capable, with proportionate variations between the timing of the exhaust valve and the volume of the working gas charge, for economical operation. It is obvious, however, that the engine will work without materially changing the power which it usually has on the slow speed, if a large charge of gas is admitted to the combustion chamber and the exhaust valve is retarded for closing late in the compression stroke of the piston, the only result being in that case, that part of the fresh gas charge will then be expelled with the burned exhaust gases of the preceding charge and wasted, the engine only catching, compressing and firing the usual small sized

charge of gas for that working adjustment of the exhaust valve.

Assuming the engine to be a vertical one, in the accompanying drawings, Figure 1 is a vertical (central) transverse section through a gas engine embodying my invention, but not showing the gas inlet throttle. Fig. 2 is a drawing showing an engine of this type and embodying my invention, having two cylinders arranged vertically, the right hand one being a side view in elevation, and the left hand cylinder showing a vertical (central) longitudinal section through the same. This figure does not show the gas throttle, but does show the gas inlet passage to the compression chamber. Fig. 3 is a side view in elevation of the cam shaft with its multiple faced cam, in engagement with the push rod wheel. Fig. 4 is another view in elevation, of the multiple faced cam and the cam guide with which it engages. Fig. 5 is a side view in elevation of the gas throttle placed in the gas inlet to the compression chamber, and its connections. Fig. 6 shows a modified connection between the throttle-operating rod and the cam-operating lever.

In the practice of my invention, I provide a cylinder 8, which is bored out truly from its lower end to the head thereof and in the center of the head is also bored to provide for the admission and fitting of the exhaust valve cage 7. The cylinder 8 is also provided at its lower end with flanges and bolt holes for fastening and fitting it to the upper part of the crank case 9. This cylinder 8 is also cast with double walls, provided in its upper portion with an annular cavity 40, through which water or other liquid is circulated for cooling purposes, and in its lower portion there is a gas passage 3 for the transferring of the power gas from the compression chamber 2 to the combustion chamber 1. This gas passage 3 opens into the combustion chamber 1, through a series of openings or ports 3' preferably entirely circling the cylinder wall, the area of said ports being approximately four fifths that of the exhaust valve and separated from each other by bridges of the cylinder wall. The lower end of this gas passage may enter either directly into the combustion chamber, or else work in connection with a series of ports, preferably, having a total or greater area than the ports 3'; these lower ports co-inciding with similar ports in the side of the piston, as 5', when the piston is at the end of its working stroke. The cylinder further contains the piston 5, carrying suitable packing rings to prevent the escape of gas past it, and being attached to the crank shaft 21 through the means of the connecting rod 22, and in its reciprocations forming the working part between the combustion chamber 1, and the compression chamber 2. These various parts are so assembled and adjusted that the

piston in its lowest point of travel uncovers the ports 3', and the piston ports 5' co-incide with similar ports in the lower part of the gas passage 3, thus affording a free means for the transfer of a charge of gas from the compression chamber 2 to the combustion chamber 1. Short bearings 10, 10, are fastened to the crank case 9, and form bearings for the crank shaft 21. The lower part of the crank case 9' is fastened to the upper part 9, and forms a gas tight part of the compression chamber, and also an oil pan for retaining a lubricating element. It also in conjunction with the upper part of the crank case 9, as shown in Fig. 1 and Fig. 2, forms the bearings 39, 39, for the cam shaft 18, while the bearings 38, 38, for the slide bar 23 are formed in a part of the upper half of the crank case 9.

The exhaust valve cage 7 is fitted in the head of the cylinder 8 and held in place by cap screws. The valve 6 works in the valve cage by a valve stem 35 passing through a suitable hole bored for its reception. The valve stem carries a head 36 on its upper end, and a helical spring 17 interposed between the valve stem head and the valve cage 7, securely holds the valve 6 to its seat. This valve 6 is operated by a rocker arm 13, pivoted near its center on an upright staff 16, said staff being securely fastened in the cylinder head. This rocker arm 13 is operated by a push rod 14 pivoted to its outer end. The push rod 14 is also pivoted near its lower end to the rocking link 33 for the purpose of holding it in proper working position, and it also carries at its lower end a cam wheel 15 working in engagement with the cam 12.

The crank shaft 21 carries a spur gear 20 working in engagement with another spur gear 19 of the same diameter which is secured to the cam shaft 18, which it causes to rotate at the same speed as the crank shaft 21. The cam shaft 18 is round in form throughout the greater part of its length, but at the points where it carries the cam 12 it is square in section for a length greater than the length of the cam 12, and thus while it provides for the positive rotation of the cam 12 which it bears with it, the cam is at the same time capable of being moved axially along the cam shaft. The cam 12 provides for the variable timing of the exhaust valve in its closing, and is made with a square hole axially throughout its length corresponding to the squared portion of the cam shaft 18 on which it seats.

The cam 12 has at one end an annular channel or groove 26 in which engages the fork 24. The cam 12 is also of a greater length than the cam wheel 15, and might be called a plurality of cams in one, comprising a series of steps cut in its working face and made of various lengths of the arc, so that the path of travel of the cam wheel 15 across

the cam 12 at its short arc end is of a comparatively short duration holding the exhaust valve open for about 105° of the full revolution of the crank shaft. But if the cam 12 is moved along the cam shaft 18 until its greatest length of arc portion is brought into engagement with the cam wheel 15, it causes the cam wheel 15 to be raised and the exhaust valve to be held open for approximately 180° of the revolution of the crank shaft. The intermediate arcs and steps in the cam 12 are variations, graduations and proportions between the two extreme adjustments, and all may be varied at the will of the constructor.

The cam 12 is moved for its adjustments by the fork 24, mounted on the slide bar 23 which is carried in bearings 38, 38, on the engine case. The fork 24 is held in position on the slide bar 23 by the collars 37, 37', and the helical spring 25 interposed between the cam and the collar 37'. In the case of a single cylinder engine, it is not necessary to use this spring 25, but where there is a number of cylinders in the engine, should one cam wheel 15 at the time of throwing or moving the slide bar 23 to the left be against one of the shoulders of a cam 12, it allows the bar to be operated and as soon as the revolution of the cam shaft 18 revolves sufficiently to disengage that cam wheel, the spring then brings that cam into proper position or adjustment with the others. The slide bar 23 is operated by the controlling lever 28 pivoted to an arm 27 secured to the engine.

The gas inlet passage 29 opens through a port into the compression chamber 2, and is opened when the lower edge of the piston 5 rises above it and is closed by the downward movement of said piston. It is connected with the outside gas piping 30 leading to the gas throttle 31 and vaporizing chamber 31'. The gas throttle 31 may be of any well known construction of the art, and is connected to the operating lever 28 by the connecting rod 32. In the construction shown in Fig. 5 it is contemplated that movement of the rod 32 and throttle to the left opens the throttle wider and increases the admission of gas, and movement to the right closes the same and restricts the admission of power gas.

Preferably, the connections between the rod 32 and the controlling lever 28 are such that they are operative co-jointly, the valve closing earlier with the wider opening of the throttle and vice versa. But they are capable of adjustment so that each can be operated independently if desired, as it does not change the spirit of this invention or the economy or efficiency of the working of the engine where they are independently controlled. Such a construction is shown in Fig. 6, where the rod 32 is provided with a

plurality of teeth 33 adapted to engage with the lower end of the loop 34 on the lever 28 through which said rod passes. A handle 35 on the end of the rod enables the attendant 5 to lift it and shift the lever to a new position of engagement when desired. Such a movement of the lever will slide the cam along the shaft 18, and will delay the closing of the exhaust-valve, without changing the position 10 of the throttle, which can be independently adjusted, if desired, before the rod is again engaged with the lever. A similar result can be effected by the construction shown in Fig. 5, by pulling out the small pin 36, which 15 allows the lever to be moved without moving the throttle. Some such construction as this is advisable, because the same explosive mixture of fuel and air does not always give the same results in power and efficiency, 20 owing to differences in temperature, atmosphere conditions, and variations in altitude, which tend to vary the ratios of expansion of the fresh cold mixture when admitted into the hot combustion chamber. 25 In order, therefore, to secure perfect efficiency under all conditions, a certain latitude of adjustment between the operation of the throttle and the exhaust valve is necessary. It will be noted that whenever the controlling lever is moved to the left, in Fig. 5, it 30 advances the time of the closing of the exhaust valve, so as to utilize a larger working charge, and at the same time the throttle is correspondingly opened to provide the increased charge, and vice versa. Ignition is 35 preferably accomplished by electrical means, either by the jump spark method, or make and break mechanism.

In operation, the upward stroke of the 40 piston draws into the compression chamber 2 by vacuous induction, a charge of power gas or vapor and air, which is compressed on the downward stroke of the piston, and on the piston passing the ports 3' of the open gas 45 passage 3, this charge then rushes into the combustion chamber 1, and is compressed and exploded, a fresh charge of gas at the same time entering the compression chamber for the next working stroke, or explosion.

50 I claim as my invention and desire to secure by Letters Patent:

1. In a gas engine, the combination of a cylinder having a combustion chamber and a compression chamber with a communicating 55 passage between them adapted to be opened by a piston at the end of its downward stroke and closed near the beginning of its upward stroke, a source of supply opening into the compression chamber having a throttle 60 therein, and an exhaust valve in the combustion chamber variably timed operatively and adjustably controllable.

2. In a two cycle gas engine, the combination 65 of a combustion chamber and a compression chamber with a communicating pas-

sage between them adapted to be opened by a piston at the end of its working stroke, a source of supply opening into the compression chamber, an exhaust valve in the combustion chamber timed to open before the 70 opening of the passages between the combustion and compression chambers, means for varying the volume of the power gas admitted to the compression chamber, and means for varying the timing of the closing 75 of the exhaust valve.

3. In a two cycle gas engine, the combination of a cylinder having a combustion chamber and a compression chamber with a communicating passage between them having a series of ports entirely encircling the combustion chamber, and adapted to be opened by a piston at the end of its working stroke, a supply port to the compression chamber mechanically opened during the 85 pistons upward stroke and closed at or near the beginning of the pistons downward stroke, an exhaust valve in the combustion chamber timed to open before the opening of the inlet ports to the combustion chamber, 90 and means for variably timing its closing points.

4. In a two cycle gas engine, the combination of a cylinder having a combustion chamber and a compression chamber with a communicating 95 gas passage between them adapted to be opened by a piston at the end of its downward stroke, a supply port opening into the compression chamber and adapted to be opened by the piston during its upward 100 stroke, and a variably timed exhaust valve in the combustion chamber mechanically operated.

5. In a two cycle gas engine, the combination of a combustion chamber and a compression chamber with a communicating passage between them adapted to be opened by a piston at the end of its downward stroke, a supply port opening into the compression chamber and adapted to be opened 110 by the piston during its upward stroke, an exhaust valve in the combustion chamber timed to open before the opening of the passage between the combustion chamber and compression chamber and variably timed 115 in its closing points, means for varying the volume of the power gas admitted to the compression chamber, and means for controlling the timing of the closing of the exhaust valve.

6. In a gas engine, the combination of a cylinder having a combustion chamber and a compression chamber with a communicating passage between them adapted to be opened by a piston at the end of its downward stroke and closed near the beginning of its upward stroke, a supply port opening into the compression chamber and adapted to be opened by the piston during its upward 125 stroke and closed during its downward stroke, 130

- an exhaust valve in the combustion chamber, a crank shaft, a cam shaft working in engagement with the crank shaft and having mounted thereon a cam consisting of a number of working arcs of different lengths, said cam rotating in unison with the crank shaft and adapted to be moved axially along its seat for variably operating the exhaust valve and means for adjusting the cam.
- 10 7. In a gas engine, the combination of a cylinder having a combustion chamber and a compression chamber with a communicating passage between them adapted to be opened by a piston at the end of its downward stroke, a supply port opening into the compression chamber and adapted to be opened by the piston during its upward stroke and having a throttle connected therewith, an exhaust valve in the combustion chamber, a crank shaft, a cam shaft working in engagement with the crank shaft and having mounted thereon a cam consisting of a number of working arcs of different lengths, said cam rotating in unison with the crank shaft and adapted to be moved axially along its seat for variably operating the exhaust valve, means for adjusting the cam, and means for adjustment and operative control of the exhaust valve and throttle co-jointly.
- 20 8. In a gas engine, the combination of a cylinder having a combustion chamber and a compression chamber with a communicating passage between them adapted to be opened by a piston at the end of its down-
- ward stroke, a supply port opening into the compression chamber and adapted to be opened by the piston during its upward stroke, a throttle in the passage conveying gas to the supply port, an exhaust valve in the combustion chamber variably timed operatively, means for controlling the timing of the exhaust valve, and means for adjusting the throttle.
- 25 9. In a gas engine, the combination of a combustion chamber having an exhaust valve therein variably timed operatively, a cam operating the exhaust valve and mounted so as to be movable along its seat, controlling means for adjusting the position of the cam, and yielding connection between the controlling means and the cam.
- 30 10. In a gas engine, the combination of a combustion chamber having a variably timed exhaust valve therein, a cam operating the exhaust valve and mounted so as to be movable along its seat, a movable controlling rod having annular collars secured thereto with a spring interposed between two collars, and a cam guide mounted on the controlling rod between one of the collars and the spring and engaging with the cam.

In testimony whereof I have signed my name to this specification in the presence of two subscribing witnesses.
